UNITED STATES PATENT OFFICE.

JOSEPH L. DICKINSON, OF CARBON HILL, ALABAMA, ASSIGNOR OF ONE-HALF TO ALVIN R. SMITH, OF SAME PLACE.

DESIGN FOR A BUTTER-MOLD STAMP.

SPECIFICATION forming part of Design No. 27,782, dated October 26, 1897.

Application filed September 14, 1897. Serial No. 651,685. Term of patent 7 years.

To all whom it may concern:

Be it known that I, JOSEPH L. DICKINSON, a citizen of the United States, residing at Carbon Hill, in the county of Walker and State 5 of Alabama, have invented a new and original Design for a Butter-Mold Stamp, of which the following is a specification.

This invention relates to a new and original design for a butter-mold stamp; and it has for 10 its object to provide a design of this character that shall be both useful and ornamental.

The leading feature of the design resides in a butter-mold stamp having a circular concavo-convex body provided in its concave 15 face with a central circular figure inclosing within the outline thereof a central cavity and a circular field of radially-disposed depressions surrounding said cavity, said circular stamp-body being further provided in its 20 concave face, between the peripheral edge thereof and said central circular figure, with a circular series of spaced outwardly-flared concavities and radially-disposed grooves extending longitudinally of the ridges between 25 said concavities.

In the drawings, Figure 1 is a perspective view of a butter-mold stamp embodying the herein-described design. Fig. 2 is a face or 30 plan view thereof. Fig. 3 is a cross-sectional view on the line 3 3 of Fig. 2.

Referring particularly to the drawings, the numeral 1 designates the circular body of the stamp, which is usually formed integrally with the handle or stem 2. In the present invention the circular body 1 is concavo-convex in 35 form and is provided in its concave face with a central circular figure "3." The figure "3" incloses a central space in which is arranged a central cavity 4, and a circular field of radially-disposed depressions 5, surrounding 40 the cavity 4. Between the figure "3" and the peripheral edge of the circular body 1 the latter is further provided in its concave face with a circular series of spaced outwardly-flared concavities 6, which concavities are separated by radially-disposed ridges 7, longitudinally of which ridges extend grooves 8, which are necessarily disposed in radial lines with respect to the center of the circular body. 50

What I claim is—

The design for a butter-mold stamp herein shown and described.

In testimony that I claim the foregoing as my own I have hereto affixed my signature in 55 the presence of two witnesses.

JOSEPH L. DICKINSON.
